UNITED STATES PATENT OFFICE.

JAMES M. ROBINETTE, OF WILLIAMSON, WEST VIRGINIA.

CUE-TIP AND FASTENING MEANS THEREFOR.

1,111,497.

Specification of Letters Patent.

Patented Sept. 22, 1914.

Application filed October 17, 1913. Serial No. 795,740.

To all whom it may concern:

Be it known that I, JAMES M. ROBINETTE, a citizen of the United States, residing at Williamson, in the county of Mingo and 5 State of West Virginia, have invented certain new and useful Improvements in Cue-Tips and Fastening Means Therefor; and I do hereby declare the following to be a full, 10 clear, and exact description of the invention, such as will enable others skilled in the art to which it appertains to make and use the same.

This invention comprehends improvements in cue tips and fastening means therefor, and has for its primary object to provide a tip which may be quickly attached to 15 and detached from a billiard cue.

Another object of the invention is to provide a tip having a plurality of arms adapted to seat within recesses formed in the end 20 of the cue, and a sleeve detachably connected to the end of the cue for holding the arms within said recesses, whereby the tip is rigidly secured in position.

25 The invention also aims to provide a cue tip and fastening means therefor which shall be of extremely simple construction, cheap to manufacture and very practical.

With these and other objects in view as 30 will become more apparent as the description proceeds, the invention consists in certain novel features of construction, combination and arrangements of parts as will be hereinafter more fully described and 35 claimed.

For a complete understanding of my invention, reference is to be had to the following description and accompanying drawings, in which—

40 Figure 1 is a side elevation, showing the end of a billiard cue and my improved tip and fastening means therefor secured thereon, Fig. 2 is a side elevation, showing the tip positioned on the end of the cue, the 45 attaching sleeve being omitted, Fig. 3 is a longitudinal sectional view taken on the plane of line 3—3 of Fig. 1, Fig. 4 is an end elevation of the cue, and Fig. 5 is a perspective view of the tip.

50 Referring in detail to the drawings by numerals, 6 designates a portion of the billiard cue having a plurality of dove-tail recesses 7 formed in the periphery thereof and opening upon the end of the cue. These

recesses extend longitudinally of the cue and 55 are preferably spaced equal distances from each other.

8 designates as an entirety the tip which includes a body portion formed of circular disks 9 and 10 and a plurality of arms 11 integral with the disk 10. These arms are formed on the inner side of the disk adjacent the perimeter thereof and increase in width as they approach their free ends. The arms are received in the dove-tail recesses 7 and are locked therein by means of a frusto-conical sleeve 12. This sleeve is formed adjacent its inner edge with a bayonet slot 13, the walls of which lockingly engage a pin 14. The tip is preferably 70 formed of leather and if desired, the body portion thereof may be made of a single piece of material instead of two layers, as shown in the drawings.

When a tip becomes worn it may be easily 75 removed by disconnecting the sleeve from the cue and drawing the arms 11 from the recesses 7.

While I have shown and described the preferred embodiment of my invention, it 80 will be understood that minor changes in construction, combination and arrangement of parts may be made without departing from the scope and spirit of the invention as claimed.

Having thus described my invention, I 85 claim:

1. The combination with a billiard cue having dove-tail recesses formed in the periphery and opening on one end thereof, of 90 a tip having a plurality of arms adapted to fit within said recesses, and means for locking the arms within the recesses.

2. The combination with a billiard cue having dove-tail recesses formed in the periphery thereof, and opening upon one end of the cue, of a tip including a circular body, and a plurality of arms formed integrally therewith and adapted to fit within said recesses, of a sleeve secured to the cue 100 and surrounding the arms to hold them within the recesses.

3. The combination with a billiard cue having dove-tail recesses formed in the periphery and opening upon one end thereof, of a tip including a circular body and a plurality of arms formed integral with said body upon the inner side thereof adjacent

the periphery of the body, said arms increasing in width as they approach their free extremities and being adapted to fit within the recesses, a sleeve mounted on the cue and holding the arms within the recesses, and means for detachably securing the sleeve to the cue.

In testimony whereof I affix my signature in presence of two witnesses.

JAMES M. ROBINETTE.
